ATTORNEYS

UNITED STATES PATENT OFFICE.

PHILIP SCHUYLER KANE, OF KANE, PENNSYLVANIA.

GOLF BALL.

Application filed July 28, 1925. Serial No. 46,643.

To all whom it may concern:

Be it known that I, PHILIP S. KANE, a citizen of the United States, and resident of Kane, in the county of McKean and State of Pennsylvania, have invented certain new and useful Improvements in Golf Balls, of which the following is a specification.

My present invention relates generally to golf balls and more particularly to an arrangement and construction having for its primary object to prevent the loss thereof as well as to eliminate the frequent delays and added burden of hunting golf balls driven into long grass, ditches and other hazards of golf courses.

My present invention has for its more particular object the provision of a golf ball provided with signal means, preferably visible signal means, which will permit the owner and others to tell exactly where to find the ball in tall grass for instance where it would ordinarily be difficult and require time to find.

In the accompanying drawing which illustrates my invention and forms a part of this specification,

Figure 1 is a plan view of a golf ball constructed in accordance with my invention.

Figure 2 is a sectional view taken therethrough.

Figure 3 is a similar view taken on line 3-3 of Fig. 2, and

Figure 4 is a detail perspective view of the several parts of my invention, removed.

Referring now to these figures and particularly to Figs. 1, 2 and 3, my invention contemplates any of the well known makes of golf balls such as generally indicated at 10, provided in its surface with an elongated cavity 11 of the arcuate form shown and of the same depth throughout its length.

The cavity 11 thus formed is adapted and intended to receive an elongated thin wall casing 12 which in turn may receive slow-burning powder or other smoke producing mixture as for instance a squib 17 such as shown in Fig. 4.

The casing 12 may be held in place either by forcing the same into the cavity 11, or

may be anchored by a bolt 14 of small diameter extending diametrically through the golf ball 10 as shown particularly in Fig. 2. In the event that the bolt 14 is utilized, it may be made to serve the further function 55 of balancing the casing and its parts so as to maintain true flight and roll of the ball.

The casing 12 has a cover 10^a which may be hinged at one end to the casing or adapted to clasp in connection therewith. This 60 cover or lid 10^a is preferably slightly shorter than the casing in order to leave a small opening by which to permit of the entrance of sufficient air to support combustion.

Moreover the walls of the casing 12 are 65 preferably provided along the edges thereof with turned flanges 16 which lap the adjacent edges of the cover 10^a of the ball in order to hold the same and prevent the cover from readily cracking and breaking. 70

In Figs. 2 and 4 I have shown a squib 17 with a short fuse 18 which is lighted before the ball is driven so that its flight may be more readily traced and the spot where it finally comes to rest may be easily seen. By 75 virtue of the slow burning power of squib and the emission of smoke for a considerable period no trouble is encountered in locating the ball even in high grass where this is ordinarily a difficult matter. 80

It is understood that except for the necessary slight opening previously mentioned for the purpose of supporting combustion, the casing and its cover or lid fill out the normal contour of the ball and form a part 85 of its external surface.

I claim:

1. A golf ball, and means in connection therewith for emitting smoke whereby to signal the position of the ball after flight. 90

2. A golf ball having a cavity, and means forming a slow burning squib in said cavity.

3. A golf ball having a cavity, a covered casing in said cavity, and a squib in said casing. 95

4. A golf ball having a surface cavity, a casing in said cavity, a squib in the casing, and a lid for the casing forming thereof a part of the external surface of the ball.

PHILIP SCHUYLER KANE.
